CLAIM

The ornamental design for a light shade for a ceiling fan, as shown and described.

DESCRIPTION

FIG. 1 is a bottom perspective view of a light shade for a ceiling fan showing our new design in the environment of a ceiling fan;

FIG. 2 is a top perspective view the light shade of FIG. 1, shown without environment.

FIG. 3 is a top view thereof.

FIG. 4 is a bottom view thereof; and,

FIG. 5 is a side view thereof.

Broken lines in FIG. 1 illustrate environmental subject matter and form no part of the claimed design. Additional broken lines in FIGS. 2-5 illustrate portions of the light shade and form no part of the claimed design.

1 Claim, 5 Drawing Sheets(56)
